CLAIM

The ornamental design for a flashlight, as shown and described.

DESCRIPTION

FIG. 1 is a perspective front view of a flashlight showing our new design;

FIG. 2 is a top plan view thereof;

FIG. 3 is a side elevational view of the right side of the flashlight, the left side being a mirror image thereof;

FIG. 4 is a bottom plan view thereof;

FIG. 5 is a front elevational view of the flashlight design;

FIG. 6 is a rear elevational view thereof;

FIG. 7 is a perspective view of an alternate embodiment of our new flashlight design;

FIG. 8 is a top plan view thereof;

FIG. 9 is a side elevational view of the right side of the alternate embodiment, the left side being a mirror image thereof;

FIG. 10 is a bottom plan view thereof;

FIG. 11 is a front elevational view of the alternate embodiment; and,

FIG. 12 is a rear elevational view thereof.
